UNITED STATES PATENT OFFICE

HENRY MOECKER, JR., OF FLOSSMOOR, ILLINOIS, ASSIGNOR TO AMERICAN STOVE COMPANY, OF ST. LOUIS, MISSOURI, A CORPORATION OF NEW JERSEY

INSULATED RANGE

Application filed September 19, 1929. Serial No. 393,757.

This invention relates to improvements in insulated ranges the invention being more specifically directed to the construction of the broiling and cooking ovens of a range and the lining therefor.

5 The primary object of the invention is the provision of an improved construction of broiling and cooking ovens for ranges.

A further object of the invention is the 10 provision of an improved box lining for the broiling and cooking ovens of a range.

Another and further object of the invention is the provision of an improved box lining for the broiling and cooking ovens of a 15 range, said lining having an improved flue arrangement and being constructed to slide as a whole into a standard sized broiling and cooking oven of a standard range.

A still further object of the invention is 20 the provision of a box lining for the cooking and broiling oven of a range and a new manner of assembly of the oven back wall to the body portion of the oven compartment.

A still further object of the invention is 25 the provision of a construction to accomplish the purposes above described which is simple and cheap of construction, highly efficient in operation, and one which materially cheapens the cost of assembly of a range by materially 30 reducing the amount of time required in the assembly of the broiling and cooking ovens and the lining therefor.

Other specific objects, novel features of construction and improved results and improved 35 operation of the broiling and cooking ovens and lining therefor will appear from the following description and accompanying drawings.

In the drawings:

40 Figure 1 is a view in strung out perspective of a broiling and cooking oven of a range with the oven back removed, the box lining for the ovens and the oven back wall.

Figure 2 is a perspective view of the box 45 lining for the ovens, a portion of the view being broken away and shown in vertical section.

Figure 3 is an enlarged fragmentary vertical sectional view through the top rear corner of the assembled oven construction with

the improved box lining and flue way in position.

Figure 4 is an enlarged fragmentary vertical sectional view through the front end of the box lining illustrating the construction 55 of that part of the lining.

Reference now being had to the drawings it will be seen that the oven proper comprises a bottom 5, side walls 6 and 7, and a top 8, all of which are supported upon and in a 60 bottom frame 9 and a front frame 10. The front frame carries an oven door 11 and a broiler door 12 which close the front of the oven structure while the rear of the oven structure is closed by the oven rear wall 13. 65

The range is of the insulated type and is provided at the inner sides of its walls and top with a suitable insulating material 14 and in the assembly of the ovens this is put into place before the box lining is slid into 70 the oven housing.

The box lining for the oven is composed of two side walls 15 and 16, a rear wall 17 and a top composed of two members 18 and 19 arranged throughout the majority of their 75 areas in separated parallel relation forming between them a space 20. This box lining is preferably made of copper bearing material, although other materials could be readily substituted, and in the assembly the side walls are provided with flanges 21 and 22 overlapping the rear wall of the lining and welded thereto, although the parts could be bolted or riveted. The piece 18 constituting the top of the lining at its longitudinal edges 80 is bent downwardly as at 23 to meet the lining top piece 19 and has a portion 24 which parallels and abuts the top piece 19 for a short distance. These horizontally disposed shoulders or flanges 24 terminate in right-angle bends forming vertical flanges 25 which parallel the outer faces of the upper ends of the lining side walls. The upper ends of the lining walls are bent inwardly at right- 85 angles to form longitudinal flanges 26 and it will be seen that the outer longitudinal edges of the top piece 19 are positioned between the flanges 26 of the side walls and the horizontal portions 24 of the top piece 18. The parts 90

95

100

being positioned as thus described are welded or otherwise suitably fastened together.

The rear wall 17 of the lining is provided with a flue outlet 27 which communicates with the vertical flue-way 28 which is welded or otherwise suitably attached to the rear face of this lining member.

The lining top at its rear edge is bent downwardly to form a flange 29 which is welded or otherwise suitably attached to the upper edge of the rear wall of the lining but this flange is cut away intermediate its length to form an opening 30 having communication with the space 20 between the lining top members 18 and 19.

In the assembly of the cooking and broiler ovens the back wall 13 of the oven compartment is left off and the box lining is shoved or slid as an entirety into the oven housing with the open front end of the lining towards the oven and broiler doors and the open bottom of the lining being closed by the bottom 5 of the oven housing.

As the oven compartment comprises both the broiler and cooking oven it will be readily understood that a plate, although not shown, is provided intermediate the height of the box lining to divide the lining and the oven into the two compartments forming the broiling and cooking ovens. This division plate which forms the top of the broiling oven and the bottom of the cooking oven is positioned in a horizontal line in a plane intermediate the top of the broiling oven door 12 and the bottom of the cooking oven door 11, while the flue opening 27 is positioned centrally of the lining rear wall 17 from side to side and just above where this division plate forming the bottom of the cooking oven 40 will come.

Of course it is essential for every oven to have a burner and a gas supply therefor, and as a consequence the oven housing wall 7 is provided with an opening 30 while the box lining wall 16 is provided with an aligned opening 31 for the passage of the burner mixing tube or the fuel supply pipe.

Most ranges today also have an oven thermostatic control and to accommodate this apparatus the box lining wall 16 is provided with an opening 32 to accommodate the control mechanism of the thermostat and an opening 33 which is partially in the lining side wall and partially in the lining top to accommodate the thermostatic member per se. The opposite oven side wall 15 is provided with an opening 34 to accommodate a bracket for supporting the outer end of the thermostatic member. As the lining top member 19 would interfere with the passage of the thermostatic member into the lining this member is provided with a transverse U-shaped bend 35 opposite the openings 32 and 34 to provide a space for the accommodation of this thermostatic member per se.

Due to this U-shaped bend 35 the space 20 terminates at its front end in the transversely extending wall 36 forming a portion of this U-shaped bend.

As has been previously explained, this box lining is slid as an entirety into the oven housing it being understood of course that the insulating material 14 has been previously positioned and suitably held in the oven housing so as to permit the ready and easy insertion of the box lining.

The housing comprising the cooking and broiling ovens is standard and identical with housings heretofore known and used with the exception that at its rear it is provided with longitudinally outwardly extending angle irons or flanges 37 and 38 and horizontally outwardly extending angle irons or flanges 39 and 40 positioned at the top and bottom of the oven housing respectively.

The rear wall 13 of the oven housing is also slightly different from what has been heretofore known as standard in that it has an encircling flange or angle iron 41 which telescopes the flanges 37, 38, 39 and 40 of the oven housing and is suitably removably attached to these angle irons by bolts 42 or the like.

When the oven housing rear wall 13 is in place it will be seen by reference to Figure 4 of the drawings that the flue-way 28 abuts the rear wall 13 of the oven housing and centrally disposed at the upper edge of the oven rear wall 13 there is provided a flue box 43 and having an opening 44 which is in communication with the upper end of the box lining flue-way 28 and the opening 30 of the space 20 at the top of the box lining.

This flue box is provided with a conventional collar 45 for the reception and support of a take-off pipe or conduit when desired.

Having described the invention it will be seen that the only outlet for the products of combustion to escape from the ovens is through the lining opening 27 and up the flue-way 28 to the flue box 43.

The separated horizontal top members 18 and 19 form at the top of the lining an air insulation and heat from this space 20 can escape through the opening 30 outwardly through the flue box 43 so that at the top of the range construction there is an air insulation in addition to the sheet insulation 14.

Due to the outwardly extending angle irons or flanges at the rear edges of the oven housing sufficient clearance is provided to accommodate the flue-way 28 of the box lining without reducing the interior dimensions of either of the ovens.

Thus it will be seen that I have provided an oven construction for ranges which is quick and simple of assembly and one which in respect to the oven housing requires no alteration other than the provision of the angle iron flanges and a slight alteration of

the oven rear wall so that the invention is readily adaptable to a standard oven and will not affect the dimensions of either the height, width or depth of the oven chambers.

5 Although it is not illustrated in the drawings for the reason that any of the well known constructions could be used, it will be understood that the interior side walls of the lining will be provided with means for slidably supporting the oven racks and such broiler pans as go into the usual make-up of this part of a cooking range.

Having thus described my invention what I claim and desire to secure by Letters Patent is:

1. An improved range construction, comprising an oven housing having a removable wall, a lining for said housing slidable into the same when said wall is removed, an outlet flue formed as a part of said lining, and said removable housing oven wall having a flue outlet adapted for communication with the oven lining flue, for the purpose described.

25 2. An improved range construction, comprising an internally insulated oven housing, and a lining for said housing slidable thereinto and directly engaging and supporting said housing insulation, for the purpose described.

30 3. An improved range construction, comprising a standard size oven housing constituting the broiler and baking ovens of the range, said housing having a removable rear wall, the rear edges of the oven housing provided with outwardly extending flanges, a lining slidable into said housing through said rear opening, said lining carrying on the outer face of its rear wall an outlet flue with an opening into the interior of the box formed by said lining, a rear wall for closing said oven housing, and said rear wall provided with a surrounding peripheral flange adapted to be attached to the flanges at the rear of the oven housing, whereby said rear oven wall is offset to accommodate the lining flue with the result that the standard dimensions of the broiling and baking ovens are not altered by the flue-way carried by the lining, and said oven housing rear wall provided with a flue outlet communicating with the lining flue-way.

35 4. An improved range construction, comprising an oven housing having a removable wall, a lining for said housing slidable into the same when the said wall is removed, an outlet flue formed as a part of said lining for the escape of the products of combustion from said oven housing, said lining at its top provided with an air space with an outlet opening adjacent the upper end of the lining flue-way, means for attaching said removable oven wall to the oven housing, and said wall provided with an outlet opening communicating with the upper end of the said

lining flue-way and the outlet opening in the space at the top of the lining, for the purpose described.

5. An improved range construction, comprising an oven housing constituting the broiler and baking ovens of the range, said oven having a removable wall and being internally insulated, means carried by said oven wall and said oven housing for attachably connecting the wall to the housing in an off-set position, a lining forming a box with an open end and bottom slideable into said housing through the opening thereof, said lining carrying on the outer face of one of its walls an outlet flue-way with an opening into the interior of the box, and said removable oven housing wall provided with a flue outlet communicating with the lining flue-way, for the purpose described.

20 6. An improved range construction, comprising an oven housing adapted to constitute and form the broiler and baking ovens of the range, said oven having a removable wall, a box lining slideable into said housing when said wall is removed, said box constituting the lining for both the broiler and baking ovens of the range and provided at one of its walls with a flue-way having communication with the interior of that part of the box lining which would form the baking oven, and said removable oven wall provided with a flue outlet communicating with said lining flue-way when the wall is in its attached position closing the oven housing side.

25 7. In combination with a cooking range having a standard size oven housing constituting and accommodating the broiler and baking ovens of the range and provided with a removable wall supported in an off-set position and provided with an outlet flue box, of a like lining slideable into said housing when the wall thereof is removed, said lining carrying on one of its walls an outlet flue-way communicating with the interior of the box and accommodated in the space provided by the off-set position of the removable wall of the housing, and the upper end of said flue-way communicating with the outlet flue carried by the removable oven housing wall, for the purpose described.

30 8. An improved range construction, comprising an oven housing constituting and accommodating both the broiler and cooking ovens of the range and provided with a removable wall, a box lining for said housing slideable into the same when the removable wall thereof is detached, and said box lining provided with an outlet flue communicating at one end with the interior of the box and at its other with the atmosphere, for the purpose described.

35 9. An improved range construction, comprising an oven housing constituting and accommodating both the broiler and cooking ovens of the range and provided with a re-

movable wall and a lining slidable into and out of said housing when the removable wall thereof is detached, for the purpose described.

5 10. An improved range construction, comprising an oven housing constituting and accommodating both the broiler and cooking ovens of the range and provided with a removable wall, a lining for said housing slid-
10 able into the same when the removable wall thereof is detached, and said lining provided with an outlet flue communicating at one end with the interior of the lined oven housing and at its other end with the atmosphere,
15 for the purpose described.

11. An improved range construction, comprising a standard size oven housing constituting the broiler and baking ovens of the range, said housing having a removable wall, the edges of the housing adjacent the opening to be closed by the removable wall provided with outwardly extending flanges, a lining slidable into said housing through said housing opening, said lining carrying on the outer 25 face of one of its walls an outlet flue with an opening into the interior of the compartment formed by said lining, a wall for closing said oven housing opening, and said wall provided with a surrounding peripheral flange 30 adapted to be attached to the flanges surrounding the oven housing opening, whereby said removable oven wall is secured in an offset position to accommodate the lining flue with the result that the standard dimensions 35 of the broiling and baking ovens are not altered by the flue-way carried by the lining, and said oven housing provided with a flue outlet communicating with the lining flue-way.

40 In testimony whereof I hereunto affix my signature.
